Specification for Design.

Patented Apr. 7, 1914.

Application filed February 9, 1914. Serial No. 817,713. Term of patent 7 years.

To all whom it may concern:

Be it known that I, EDWARD A. LARSON, a citizen of the United States, residing at Chicago, in the county of Cook and State of Illinois, have invented a new, original, and ornamental Design for a Temperature-Indicator, of which the following is a specification, reference being had to the accompanying drawings, forming a part thereof.

In the drawings:—Figure 1 is a face view showing in elevation a temperature indicator made in accordance with my new design. Fig. 2 is a side elevation of the same.

I claim:—

The ornamental design for a temperature indicator as shown.

In testimony whereof I have hereunto set my hand at Chicago, Illinois, this 31st day of January, 1914.

EDWARD A. LARSON.
